EXTENSIBLE CONNECTER

Jacques Kreisler, New Rochelle, and Leslie Kreisler, New York, N. Y., assignors to Jacques Kreisler Sales Corporation, New York, N. Y., a corporation of New York

Application March 13, 1936, Serial No. 68,604

13 Claims.

(Cl. 24—71)

The present invention relates to extensible connectors for bracelets, wrist watch straps, wrist bands, and the like.

The extensible connectors, with which the present invention is more particularly concerned, is of the type which comprises a plurality of sections which are pivotally connected together in foldable relation, and in which one of the sections, usually the keeper or housing section, comprises relatively slidable members. Connecters of this type may be readily adjusted to increase or decrease the circumferential length of bracelets provided therewith, a major adjustment being obtained by folding and unfolding said sections and a final adjustment being obtained by relative movement 15 between the keeper and the member slidable therein.

Heretofore, the adjustment of the slidable member in relation to the keeper has been obtained in several ways, none of which has proved entirely satisfactory. For example, in one proposed construction the member slidable in the keeper is adjustable to reduce the encircling size of the bracelet when the other sections of the keeper are in folded relation, but cannot be moved to increase the encircling size of the bracelet unless the other sections are wholly or partially unfolded. In connectors of certain other constructions, provision has been made to permit adjustment of the 20 slidable member for both increasing and decreasing the size of the bracelet regardless of whether the other sections of the bracelet are folded or unfolded. However, in said last mentioned constructions, it is necessary in order to adjust the 25 slidable members in relation to each other to provide special means for releasing the relatively slidable members. The provision of such means is objectionable because, among other things, it complicates the construction of the connector, 30 involves additional elements, and necessitates the provision of slots or other openings in the side walls of the housing member.

One of the objects of the present invention, therefore, is to provide an extensible connector 45 of the foldable and slidable link type in which the slidable links can be adjusted in both directions, that is, for increasing and decreasing the size of the bracelet, without unfolding the pivotally connected links, without the provision of additional releasing mechanisms, and without providing slots or other openings in the housing member of the connector.

Another object of the invention is to provide an 50 extensible connector comprising foldable links

with means for positively locking the pivotally connected links in folded position.

A further object is the provision of an extensible connector of the foldable and slidable link type in which the foldable links are locked in 5 folded position under the control of the relatively slidable links.

A yet further object of the invention is generally to simplify the construction and operation of extensible connectors of the class described. 10

The above objects of the invention and other objects ancillary thereto will best be understood from the following description considered with reference to the accompanying drawing forming a part of the present specification. 15

In the drawing:

Fig. 1 is a perspective view of the connector in folded condition with the relatively slidable members in fully contracted relation;

Fig. 2 is a bottom perspective view of the connector in unfolded condition and with the relatively slidable members in fully extended position; 20

Fig. 3 is a bottom plan view, on an enlarged scale and partly in section, of one of the slidable members and a part of the other slidable member; 25

Fig. 4 is a fragmentary perspective view, on an enlarged scale and with parts broken away, illustrating the arrangement for locking the pivotally connected members in folded position; 30

Fig. 5 is a sectional view on the line 5—5 of Fig. 1;

Fig. 6 is a sectional view on the line 6—6 of Fig. 3;

Fig. 7 is a sectional view on the line 7—7 of Fig. 4; 35

Fig. 8 is a sectional view on the line 8—8 of Fig. 7.

Referring to the drawing in detail, the connector 10, constructed in accordance with one embodiment of the present invention, comprises three sections 12, 14 and 16 which are pivotally connected in foldable relation. The section 12 is a housing or keeper for the sections 14 and 16 and also for the slidable member 18. The section 14 is arranged to fold within the section 16 about the pivot 20 and said sections 14 and 16 are constructed and arranged to fold within the section 12 about the pivot 22. The slidable section 18 can be adjusted with respect to the keeper 12 both in the folded and unfolded condition of said foldable sections, thus obviating the necessity for unfolding the buckle in order to obtain the sliding adjustment.

The keeper 12 is a longitudinally curved chan- 55

nel member having side walls 24 which are provided with inturned edge portions 26 forming a guide for the slidable section 18 which has a longitudinal curvature similar to that of said keeper. The slidable section 18 comprises a U-shaped channel member having its closed end 28 disposed at all times within the keeper 12 and having its free end 30 disposed at all times externally of said keeper. The legs of the U-shaped member 10 are integral with the closed end portion 28 and comprise spaced front walls 32 and 34 having side walls 36 and 38, respectively. Said side walls 36 and 38 are provided with inturned edge portions 40 and 42, respectively, which together with 15 said side walls and the front walls 32 and 34 form channels.

The U-shaped member 18 is made of spring metal and the legs of said member may be resiliently bent toward each other. The closed end portion 28 of said U-shaped member is provided with a cut-out 44 adjacent one leg of said U-shaped member to increase the resiliency of the latter in relation to other parts of said member. In accordance with the present invention, provision is made for releasably engaging the member 18 with the keeper 12 to permit relative adjustment thereof independently of the foldable sections 14 and 16 of the connector. For this purpose, interengaging means are provided on the keeper 12 and on the member 18, respectively, in the form of pawl and ratchet elements which are provided on the keeper 12 and on the member 18, respectively. As here shown, the end of the side wall 24, remote from the pivot 22, is provided with an inturned portion 46 forming a pawl or detent which engages in one of a plurality of spaced recesses or openings 48 of the ratchet formed in the side wall 36 of the member 18. Thus, as will be readily apparent, when the member 18 is moved inwardly of the keeper 12 from the position illustrated in Figs. 2 and 3 toward the end of the keeper to which the sections 14 and 16 are pivoted, the detent 46 will engage the side wall 36 of the member 18 and will be positioned within one of said openings 48 to permit movement of the member 18 inwardly of the keeper to decrease the size of the bracelet. The outer surface 50 is rounded or otherwise shaped to ride over the portions 37 of the side wall 36 between said openings 48 as the member 18 is moved to bracelet constricting position. For the purpose of holding said members 18 and 12 in the desired relative position, the arrangement of the detent 46 in relation to the ratchet, constituted by the spaced openings 48, is such that the member 18 is releasably held against movement to bracelet extending position, and for this purpose the free edge 52 of the in-turned portion or detent 46 is disposed to lie within the opening 48 in the normal position of the legs of the U-shaped member. The ratchet constituted by said openings may be withdrawn from operative engagement with the detent 46 by pressing on the ends 58 and 60 of the legs of the member 18 so as to release the edge 52 of the detent 46 from engagement with the portions of the side wall 36 adjacent the openings 48.

While the inherent resiliency of the U-shaped member 18 will be sufficient for releasably locking the detent 46 with the ratchet on the member 18, additional spring means may be provided for that purpose. In the form of the invention here illustrated, said additional spring means comprises a compression spring 62 which encircles a reduced shank portion or pin 64 provided on the

end 60 of the member 18. Said spring bears on the end of a sleeve 68 formed on the end 58 of said member 18 and on the shoulder 83 formed on the end 60. The spring 62 is concealed by a sleeve 68 fixed to a second sleeve 70 which is pivotally connected to the adjacent link 71 of the bracelet. As shown, the pin 64 is loosely received in said sleeve 68 and is movable therein. Thus, by pressing on the ends 58 and 60 at the open end of the U-shaped member, the ratchet, provided in the side wall 36, is disengaged from the detent 46 so that said member 18 can be readily moved outwardly of the keeper 12 to the desired position. 5 10

The outward slidable movement of the member 18 is limited by an inturned portion 72 of the keeper 12 in position to engage the closed end portion 28 of the member 18. Said inturned portion 72 is positioned, also, to engage the inner edge 14 of the wall 34 thereby providing, in addition to the channels in the member 12, additional guide means for the member 18, and further preventing movement of the wall 34 toward the wall 32. By thus preventing lateral movement of the wall 34 in relation to the keeper 12, all of the lateral movement of the open end of the U-shaped member is effective to engage and disengage the pawl and ratchet mechanism. 18 20 25

An important feature of the present invention resides in providing for the positive locking of the foldable sections of the connector in folded position. This is accomplished in the form of the invention herein illustrated by providing the side walls 16 of the member 18 with cut-turned edge portions 78 so constructed and arranged as to be slidably received within the channels formed in the U-shaped member 18, said channels being defined by the walls 32 and 34 overlying inturned edge portions 40 and 42, respectively, as described above. Said out-turned edge portions 78 terminate, as indicated at 80, in spaced relation to the pivoted end of said member 18. The operation of the locking device is best shown by Figs. 4 and 5. When the member 18 is adjacent its outermost position with respect to the keeper 12, and when the links 14 and 16 are folded within said keeper, the out-turned end portions 78 are in alignment with the channels in said member 18, the ends 80 of said out-turned edge portions 78 being disposed at a short distance from the adjacent edges of said channels. Upon movement of the member 18 inwardly of the keeper 12, said out-turned edge portions 78 are received within the channels of the member 18, as illustrated in Fig. 5, and are thereby held against unfolding. In order to permit unfolding of the members 14 and 16, the slideable member 18 is moved outwardly of the keeper until it reaches the position illustrated in Fig. 4 when the ends of the channels clear the edges 80 of said out-turned portions and thereby release said folded sections from engagement with the member 18 and permit unfolding thereof.

It is thus seen that the construction herein shown and described is well adapted to accomplish the several objects of the present invention. It will be understood, however, that the invention is capable of other embodiments and that the present embodiment, while preferred, is capable of variations and changes in the construction and arrangement of parts without departing from the principles of the invention. It will be understood, also, that certain parts of the connector herein shown and described may be used without others. Therefore, we do not 65 70 75

wish to be limited precisely to the construction herein shown, or to all of the elements thereof in combination, except as may be required by the appended claims.

5 Having thus described our invention, what we desire to claim and secure by Letters Patent of the United States is:

1. An extensible connector for wrist watches, bracelets, wrist bands and the like, comprising a plurality of sections pivotally connected together in foldable relation, one of said sections comprising two members arranged to slide endwise, one upon the other, said members having interengaging means for holding them in adjusted position independently of the other pivotally connected sections, one of said members having an end portion disposed between the ends of the other of said members and spaced relatively movable side portions fixed to said end portion and terminating in relatively-movable end portions extending beyond said other member, said side portions being operative in response to relative movement thereof toward each other to release said interengaging means.

25 2. An extensible connector for wrist watches, bracelets, wrist bands and the like, comprising a plurality of sections pivotally connected together in foldable relation, one of said sections comprising two members slidably adjustable endwise, one upon the other, one of said slidable members having relatively movable side portions extending lengthwise of the other of said members, one of said side portions comprising a ratchet engageable with a detent on said other member and movable with one of said side portions laterally of said other member at a point beyond one end of the latter for disengaging said ratchet from said detent.

3. An extensible connector for wrist watches, bracelets, wrist bands and the like, comprising a plurality of sections pivotally connected together in foldable relation, one of said sections comprising two members slidably adjustable endwise, one upon the other, one of said slidable members comprising a resilient U-shaped member having relatively movable side portions extending lengthwise of the other of said members, one of said side portions comprising a ratchet engageable with a detent on said other member and movable with one of said side portions laterally of said other member at a point beyond one end of the latter for disengaging said ratchet from said detent.

4. An extensible connector for wrist watches, bracelets, wrist bands and the like, comprising a plurality of sections pivotally connected together in foldable relation, one of said sections comprising two members slidably adjustable endwise, one upon the other, one of said slidable members comprising a resilient U-shaped member having relatively movable side portions extending lengthwise of the other of said members, one of said side portions comprising a ratchet engageable with a detent on said other member and movable with one of said side portions laterally of said other member at a point beyond one end of the latter for disengaging said ratchet from said detent, and means engageable with the other side portion of said U-shaped member to prevent lateral movement thereof in relation to said other relatively slidable member.

75 5. An extensible connector for wrist watches, bracelets, wrist bands or the like, comprising two members arranged to slide endwise, one upon the other, one of said members comprising an end

portion and spaced longitudinally extending and relatively movable side portions fixed at one end thereof to said end portion and terminating beyond said other member in relatively movable end portions, interengaging means on one of said side portions and on a portion of said other member, said interengaging means being releasable upon relative movement of said end portions in one direction to release said interengaging means.

10 6. An extensible connector for wrist watches or other bracelets, straps, bands and the like, comprising a first member and a second member slidably endwise, one upon the other, said first member having side walls provided with inturned edge portions forming guide means for said second member, a detent on the inner surface of one of said side walls, said second member having a side wall provided with ratchet forming means, said side wall of the second member extending lengthwise beyond one end of said first member and movable in a direction transversely thereof to release said ratchet from said detent, a third member pivotally connected to said first member and foldable into position between said inturned edge portions, and means operative upon sliding movement of said second member to telescoped position relative to said first member to lock said third member in folded position.

20 7. An extensible connector for wrist watches or other bracelets, straps, bands and the like, comprising a first member and a second member slidably adjustable one upon the other, releasable interengaging means on said members for holding them in adjusted position, a third member pivotally connected to said first member and foldable in relation thereto, and relatively slidable means on said second and third members operative when said third member is in folded position and when said slidable members are in a predetermined relative position to releasably lock the said third member in said folded position.

25 8. An extensible connector for wrist watches or other bracelets, straps, bands and the like, comprising a first member and a second member slidably adjustable one upon the other, releasable interengaging means on said members for holding them in adjusted position, a third member pivotally connected to said first member and foldable in relation thereto, said third member having out-turned edge portions, and said second member having inturned edge portions constructed and arranged to overlie said out-turned edge portions when said third member is in folded position and when said second member is in a predetermined position in relation to said first member whereby to releasably lock said third member in folded position.

30 9. An extensible connector for wrist watches or other bracelets, straps, bands and the like, comprising a first member and a second member slidably adjustable one upon the other, releasable interengaging means on said members for holding them in adjusted position, a third member pivotally connected to said first member and foldable in relation thereto, and means operative only in a predetermined position of said second member in relation to said first member for locking said third member in folded position.

35 10. An extensible connector for wrist watches, bracelets, wrist bands or the like, comprising two members arranged to slide endwise, one upon the other, one of said members comprising in integral relation an end portion and two spaced longitudinally extending side portions, means for limiting

- the movement of said end portion of one of said members between the ends of the other of said members, a detent on said other member, ratchet means on one of said longitudinally extending side portions normally in engagement with said detent to releasably hold said relatively slidible members in adjusted position, said longitudinally extending side portions terminating in end portions relatively movable toward each other beyond the adjacent end of the other member to release said ratchet means from engagement with said detent.
11. An extensible connector for wrist watches, bracelets, wrist bands or the like, comprising two members arranged to slide endwise, one upon the other, one of said members comprising in integral relation an end portion and two spaced longitudinally extending side portions, means for limiting the movement of said end portion of one of said members between the ends of the other of said members, a detent on said other member, ratchet means on one of said longitudinally extending side portions normally in engagement with said detent to releasably hold said relatively slidible members in adjusted position, said longitudinally extending side portions terminating in end portions relatively movable toward each other beyond the adjacent end of the other member to release said ratchet means from engagement with said detent, and means for operatively connecting said relatively movable end portions to one end of the bracelet.
12. An extensible connector for wrist watches or other bracelets, straps, bands and the like, comprising a first member and a second member

movably adjustable in relation to each other, interengaging means on said members for holding them in adjusted positions, a third member pivotally connected to said first member and foldable in relation thereto, and means operative in one predetermined position of said second member in relation to said first member for releasably locking said third member in folded position and automatically operative to release said third member in another predetermined position of said second member in relation to said first member.

13. An extensible connector for wrist watches, bracelets, wrist bands or the like, comprising two members arranged to slide endwise, one upon the other, one of said members comprising an end portion and spaced longitudinally extending and relatively movable side portions fixed at one end thereof to said end portion and terminating beyond said other member in relatively movable end portions, interengaging means on one of said side portions and on a portion of said other member, said interengaging means being releasable upon relative movement of said end portion in one direction to release said interengaging means, a member pivotally connected to one of said slidible members and foldable thereover, and means for releasably locking said pivotally connected member in folded position operative automatically to release the latter upon relative movement of said slidible members to a predetermined extent in one direction.
